UNITED STATES PATENT OFFICE.

ALEXANDER G. McADIE, OF SAN FRANCISCO, CALIFORNIA.

COMBINATION THERMOGRAPH AND HYGROGRAPH.

974,684.

Specification of Letters Patent. Patented Nov. 1, 1910.

Application filed March 22, 1910. Serial No. 551,023.

(DEDICATED TO THE PUBLIC.)

To all whom it may concern:

Be it known that I, ALEXANDER G. McADIE, an employee of the Department of Agriculture of the United States of America, residing at San Francisco, whose post-office address is San Francisco, California, have invented a new and useful Combination Thermograph and Hygrograph.

This application is made under the act of 10 March 3, 1883, chapter 143 (22 Stat., 625), and the invention herein described and claimed may be used by the Government of the United States or any of its officers or employees in the prosecution of work for the 15 Government, or any person in the United States, without payment to me of any royalty thereon.

My invention relates to a combination thermograph and hygrograph adapted to 20 record the degree of temperature and simultaneously indicate the percentage of saturation.

The object of my invention is to produce 25 an instrument which will record temperature and at the same time give a reliable and ready record of the percentage of saturation, reducible in grains of water vapor per thousand cubic feet, or any unit of volume which may be selected. The instrument is 30 specially designed to enable fruit growers and agriculturists in general to study atmospheric conditions intelligently for the purpose of ascertaining the times when frost is impending. It has been known for a long 35 time that on nights when the relative humidity was high a fall in temperature was less likely to be followed by frost with injurious effect upon vegetation, than on nights when the relative humidity was low. Heretofore, it has been the practice to use the 40 dew-point in foretelling frost. It is, however, not easy to use any of the ordinary forms of dew-point apparatus to accomplish this purpose. Tables are required and computation is necessary. No form of the dry 45 and wet bulb thermometer, the sling psychrometer or whirling apparatus known to the inventor gives a continuous record of temperature and humidity in such a manner that a fruit grower may readily determine what is known as the saturation deficit. There are certain methods known to orchardists for preventing injury to fruit trees by 50 frost, but it is necessary for the intelligent

application of these methods, that the fruit 55 grower shall know as much as possible of weather conditions, particularly with respect to temperature and the water vapor content. My invention will enable fruit growers to observe such temperature and degree of saturation and thereby determine the probability 60 of the occurrence of frost.

My invention is furthermore adapted for use in hospitals, assembly rooms, curing and drying rooms, or for any purpose where 65 knowledge of what may be called "the drying capacity of the air" is needed.

With the above stated general objects in view, as well as other objects which will appear from the specification and claim to 70 follow, the invention resides in the novel construction, combination and coöperation of parts hereinafter described, and particularly pointed out in the claim.

In the drawings, Figure 1 is a side perspective view of my invention, and Fig. 2 is also a side perspective view of my invention showing the hair arrangement.

Referring to the drawings, A represents a revolving cylinder or chronograph, driven 80 by clock work. On this cylinder, A, a sheet of paper, B, properly graduated according to the desired use of the instrument, is placed.

D indicates the base for supporting the 85 thermograph outfit. This outfit consists of the usual mechanical parts employed for operating the ordinary thermograph.

E is the metallic coil arranged to give motion by expansion and contraction with the 90 change in temperature, of a long index arm or pointer, F. The metallic coil, E, may be made of any suitable material that is sensitive to heat or cold, and its arrangement is not dissimilar to the coils used for this 95 purpose in well known thermographs. Any coil which will perform the function desired can be employed in my invention. On the end of the index arm, F, is a pen or pencil, G. The purpose of this pencil, G, is to record on the graduated paper, B, the rise and fall of the temperature as the index arm or pointer, F, responds to the action of the coil, E. In this manner, an accurate record 100 of the various changes in the temperature 105 may be made.

H represents the lower index arm, attached to the index arm, F, by means of a

pivot, J. The index arm, H, is movably arranged on the pivot, J, and is adapted to record its movements on the graduated paper, B, conveniently. The movement of the index arm, H, is regulated by a strand of hairs, L, which are attached at a point on the rear of the index arm, F, indicated by the letter, M, and extending lengthwise to a point on the rear of said arm indicated by the letter, N. The hairs L, rest on a hook or chain, O, which is adjustably attached to the arm, H, by means of an adjusting screw, P. This hook, O, hangs over the arm, F, in such a position as to leave its supporting part in the rear of the arm or pointer, F, for use in supporting the strand of hairs, L. These hairs, L, are sensitive to moisture, *i. e.*, the vapor particles in the air, and are adapted to lengthen, stretch or contract under saturation pressure. The lengthening or contracting of the hairs, L, depends upon the extent and effect thereon of saturation pressure. Any change in the tension of the hairs, L, produces a movement of the hook, O. The motion of the hook, O, is communicated to the index arm, H, by reason of the hook, O, being attached to said arm, and this motion causes the same to move upward or downward according to the degree of tension of the hairs, L. I do not confine myself to the use of hairs for accomplishing the object described, but any other forms of hygroscopic substances may be employed to perform said function.

Attached to the end of the index arm, H, is a pen or pencil, I, which serves to record on the chart or paper, B, the movement of the index arm, H.

R R represent the weights for counterpoising the index arm or pointer, F. A celluloid, aluminum or paper scale, Q, properly graduated and cut not straight but in arc, is suspended from the arm or pointer, F, and hangs in the rear of the arm or pointer, H. This arc, Q, is adapted to indicate the degree of saturation. The reading is accomplished by observing the top edge of the lower arm or pointer, H. The percentage mark shown at the top of said pointer is the percentage of saturation. When the pens or pencils, G and I, are close together, the percentage of saturation is very small, and when said pens or pencils are wide apart, the percentage of saturation is large.

55 The index arms or pointers, F and H, may be constructed of German silver, thin brass, steel or aluminum, or other suitable material, as may be desired.

60 In practicing my invention, I place the instrument in a proper shelter and give it suitable exposure, thus subjecting the apparatus to become sensitive to temperature and moisture in the air. The degree of temperature is recorded on the chart or paper, B, which is properly graduated, by the heat

causing the coil, E, to contract or lengthen, thereby giving motion to the index arm or pointer, F. The motion of the arm or pointer, F, is traced on the chart or paper, B, by reason of the pen or pencil, G, resting thereon, and responding to the wave or motion of said arm or pointer, F, as it becomes sensitive to the action of temperature on the coil, E. This tracing of the movements of the arm or pointer, F, on the chart or paper, B, enables the observer to read at once the degree of temperature recorded. The lower index arm or percentage pointer, H, riding upon the first index arm or temperature pointer, F, responds to temperature changes, in traveling with the long arm, F, but it also has a proper motion of its own, determined by the change in the length of the bundle or strand of hairs, L. This motion is produced by the changing of atmospheric conditions, which necessarily causes the hairs, L, to contract to stretch or expand. The changing of atmospheric conditions causing the hairs, L, to contract or lengthen, as the case may be, induces the hook, O, to move either upward or downward according to the degree of saturation in the air. The hook, O, being attached to the arm or pointer, H, necessarily communicates such upward or downward motion to said arm or pointer. The upward or downward motion of the arm or pointer, H, determines the percentage of saturation in the air.

65 In determining the percentage of saturation in air by the instrument described, use is made of a law of physics, *viz*: that for any given temperature there is at saturation a definite weight of water vapor present. As temperature changes, the saturation pressure changes, the saturation pressure being the pressure exacted by the vapor particles. The weight of the aqueous vapor, sometimes called the absolute humidity, is given by my invention directly on scale reading for different temperatures. A range of temperature from 20° F. to 60° F. is printed on the paper, B, and temperatures may be read to half a degree between these limits. There is also printed on the said paper, B, opposite to the said range of temperature, the corresponding number of grains of water vapor at the given temperature in a thousand cubic feet of space. The metric system may be employed to effect such reading and I consider this the preferable system to use. Corresponding metric values would be -6.7° C. to +15.6° C. and the weights per thousand cubic meters of saturated vapor 2870 grams to 13182 grams. The arc, Q, contains a scale showing the percentage of saturation. The reading is direct and little computation is necessary, and what there is in tenths. For example: Suppose the upper index arm or pointer, F, indicates 2800

100

105

110

115

120

125

130

grains (40° F.), the lower arm or pointer, H, reads 1935 grains (30° F.). The result would be that reading on the arc scale, Q, would be 50%. This means that a condition of half saturation exists, or that about 1400 grains of water vapor per thousand cubic feet must be added to the amount present before saturation is reached.

Having thus described my invention, I 10 claim—

A combination thermograph and hydrograph, consisting of a cylinder driven by 15 clock work, having a paper attached thereto properly graduated, and the saturation content printed in weight thereon for given 20 temperatures, a coil adapted to expand or contract with any change in temperature, a support therefor, an arm in contact with said coil, an arm in contact with said coil having counterbalancing weights at its rear 25 end and a pencil at its front end, resting on said paper, said arm having an upward or downward motion induced by the expansion or contraction of said coil, said pencil tracing the movements of said arm on the said paper, thereby recording the degree of temperature, said arm having movably attached

thereto at a lower angle and responding to its motion a second arm, said lower arm having a pencil at its front end, a hook attached 30 thereto and connecting a strand of hairs arranged lengthwise of the rear side of said first mentioned arm, said hairs being adapted to lengthen or contract with the change of saturation pressure thereby subjecting said 35 hook to an upward or downward motion as the said hairs lengthen or contract, said hook communicating such upward or downward motion to the lower arm, said arm having contact with said paper and tracing its 40 movement thereon, a percentage scale suspended from said first mentioned arm, said apparatus being adapted to record simultaneously the degree of temperature and indicate the moisture content in weight and percentage of saturation deficit, substantially as 45 described.

In testimony whereof, I affix my signature in the presence of two subscribing witnesses.

ALEXANDER G. McADIE.
